(57) **CLAIM**

We claim the ornamental design for a pet feeder, as shown and described.

DESCRIPTION

FIG. 1 is a front elevation view of a pet feeder showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom view thereof;

FIG. 7 is a front perspective view thereof; and,

FIG. 8 is a rear perspective view thereof.

The broken lines depict unclaimed features of the pet feeder, shown for purposes of illustration, that form no part of the claimed design.

1 Claim, 8 Drawing Sheets
